[57] **CLAIM**

The ornamental design for a frame with vertically mounted trailer hitch, as shown and described.

DESCRIPTION

FIG. 1 is a perspective view of the frame with vertically mounted trailer hitch taken from the top, front and right side;

FIG. 2 is a front elevational view;

FIG. 3 is a rear elevational view;

FIG. 4 is a top plan view;

FIG. 5 is a bottom plan view; and,

FIG. 6 is a side elevational view, the opposite side being a mirror image thereof.

The broken line showing of a portion of a vehicle is for illustrative purposes only and forms no part of the claimed design.
